STEAM HYDRATOR

Roy M. Schultz, Chicago, Ill., assignor to David A. Freeman Corporation, Chicago, Ill., a corporation of Illinois

Application December 31, 1948, Serial No. 68,717

10 Claims. (Cl. 299—84)

1 This invention relates to improvements in apparatus for supplying steam with a moisture content for use in pressing and cleaning fabrics and other purposes.

It is an object of the invention to provide a simple and relatively inexpensive apparatus requiring no moving parts, valves or other moving mechanism in the steam and water chamber and no elaborate system of valves, levers, piping or the like on the outside, and which is practical and of long life.

A further object of the invention is to provide a simple steam nipple communicating with the interior of the steam chamber and having a fixed water pipe connection to the water of condensation in the bottom of the chamber or reservoir therefor whereby steam with the desired water content may be discharged through a suitable outlet conduit connected to the other end of the nipple.

A still further object is the provision of a simple steam suction nipple connected directly with the steam chamber and having a water pipe connection to the water supply so that the passage of the steam through the nipple may suck its water content from the reservoir and diffuses it throughout the discharged steam.

Further objects and advantages of the invention, including several specific forms of the nipple and its arrangement will appear from the description and claims to follow in connection with the accompanying drawings which illustrate the apparatus, by way of example, but not of limitation, and several specific forms of the nipple, and in which

Figure 1 is a view of an ironing table with a steam hydrator of this invention applied thereto;

Fig. 2 is a vertical sectional view on an enlarged scale of the steam-condensing chamber and water mixer or injector and outlet valve, as used in Fig. 1;

Fig. 3 is a similar sectional view of a different form of steam-containing chamber and Venturi type of injector or mixer; and

Fig. 4 is a similar sectional view of a different arrangement of condenser chamber and Venturi type injector.

Referring first to Fig. 1, a spotting table or head, generally indicated by 10, is supported by column or columns 11 and a suitable base 12. To the rear of the table, suitably secured in any desired way, is a steam and condensing chamber 13, which is enclosed and connected to or in the steam supply by the inlet pipe 14 and the outlet or return pipe 15, the latter extending above the

bottom of the chamber, as shown in Fig. 2, to cause a quantity of water of condensation to collect therein before overflowing into pipe 15 and which reservoir water may be withdrawn for hydrating the steam for application to the garments or material on the bed 10.

On the top of box or chamber 13 a stop valve 16 is located, and this is connected by flexible tube 17 with the hand-manipulated spray head or nozzle 18, which is preferably a simple spray head controlled by the valve 16, though for convenience a lever 19 may be provided on the head 18. The flexible tube, when not in use, may be hung over forked support 20 rising from the table or bed 10. The stop control valve 16 may be opened by the depression of foot pedal 21 near the front of the machine, which foot pedal 21 is suitably connected by shaft 22 with a lever 23 and link rod 24 with the short cross lever 25. Lever 25 may be pivoted at 26 on bracket 28 projecting from the housing of stop valve 16. The outer end of lever 25 may straddle valve stem 26 between upper and lower collars 26' for raising and lowering valve member 27. The body of valve 16 is connected at one side to the flexible tube 17. Removal of the pressure on the pedal 21 results in the closing of the valve 27 through engagement of lower collar 26' by the end of lever 25. This may be readily done by a suitable counterweight or counterweights on the pedal or shaft or by springs attached thereto. The valve member 27 tightly closes on its raised annular seat, as shown.

The steam mixer or injector comprises the single tubular member or nipple 28 suitably secured as by threading in the top of plate 29 of the valve box or chamber 13. The valve 16 may be threaded on the upper end of this tube or cylinder 28, as indicated. The lower part of this nipple 28 within the chamber 13 is provided with a plurality of inlet ports or passages 30, preferably cylindrical and spaced four in number and 90° apart around the circle of the tube, and the axes of which are at substantially 30° to the axis of the cylindrical bore 31 of the member 28.

The lower end of this tube 28 is internally threaded to receive the tapered upper end of the tube 32 bearing a lock nut 33 to secure the same in position in cylinder 28. In one of the embodiments, to which I do not intend to be limited, I find a very suitable working relation between the parts when the extreme upper end or tip of tube 32 projects above the lower inside limits of the ports 30 substantially one-third the diameter of said ports. That is to say, with a bore 31 of $\frac{3}{8}$ " diameter and ports 30 of $\frac{1}{8}$ " diameter, the upper

3

end of tube 32 projects $\frac{1}{8}$ " above the lowermost limits of the openings of ports 30 into the bore 31.

With this arrangement, when the stop valve member 27 is raised sufficiently by the foot pedal, the steam rushes through the inclined ports 30 in the tube 28. This tends to reduce the pressure and produce a vacuum effect at the end of tube 32, causing a suction thereon which, under the condition of the pressure in the tank and on the water, causes the water to be injected from the bore 34 of the pointed tube into the steam jet and to mix therewith to produce the desired wet steam at the spray head and nozzle 18.

In the form of steam hydrator of Fig. 3, the steam and condensing chamber corresponding to chamber 13 of Figs. 1 and 2 comprises two chambers 35 and 36, suitably supported with respect to the bed 10, the steam inlet 31 and the return pipe 38 being connected, as shown, to the larger receptacle 35. The two chambers are connected near the bottoms by a suitable pipe connection 39. The return pipe 38 provides an overflow to limit the height of the water of condensation 40, indicated by dashed lines, in the two chambers 35 and 36. The chamber 36, being separated from chamber 35, is somewhat cooler.

In this case the nipple 41 having a Venturi type bore or passage 42 through it, is suitably secured at one end to the steam chamber 35 near the top and extends over the top of chamber 36. At the opposite end, the nipple is connected by angle coupling 43 and short pipe 44 with the stop valve 16 as in the case of Figs. 1 and 2. At the reduced portion of the bore 42 of nipple 41, the upper end of tube 54 is suitably connected and extends down through packing gland 45 into the chamber 36 and into the water 40, as indicated. The relatively small bore 46 in the tube 54 opens into the nipple 41 at the restricted portion of its bore 42 so that on sufficiently opening the stop valve 16 by the pedal, the steam rushes out through the nipple 41 and produces an effective vacuum effect in the said restricted portion in the well known manner which sucks the water up through the bore 46 of the tube 54. This water mixes with the high velocity steam and is carried thereby through the flexible hose to produce a moist steam to be ejected at the nozzle 18 upon the garment being treated.

In the arrangement of Fig. 4, the nipple 47 with which its Venturi type passage 48 and water tube connection 49 are all inside the single chamber 50 corresponding to chamber 13 in Figs. 1 and 2 and chambers 35 and 36 of Fig. 3, the nipple being connected to and through the side wall of the chamber 50 and by angle coupling 51, pipe 52, to the valve 16 in the same manner as in the other figures.

In this figure the reservoir 50 is not shown complete, but it would have inlet and return steam pipes connected therewith as in the other figures and maintain a body composed of water 40 therein as before.

Here, also, the opening of stop valve sufficiently will result in a stream of high velocity steam out of the nipple 47, the suction of the water up into the restricted Venturi passage and its mixture with the steam in the issuing stream and which is carried through the hose and discharged at the spray nozzle as wet steam.

In all the foregoing forms, the simple nipple and simple plain water pipe connection result in a means for spraying dry steam by partially opening the control valve 16 by the foot pedal or steam of the desired degree of wetness by open-

4

ing the said valve still further. It is extremely simple, efficient and of relatively low cost.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

1. In apparatus of the class described, a steam chamber and water reservoir, a steam supply connected with said chamber, a nipple connected through a wall of said chamber and communicating with the interior thereof, said nipple having therein a suction-producing region upon the passage through the nipple of steam at a relatively high velocity, a water outlet pipe connected to said nipple at said region and connected with the water in the lower part of said reservoir, a steam discharge conduit connected with the outlet end of said nipple, and a valve to control the flow of steam and thereby the water through said conduit according to the extent of opening of said valve.

2. In apparatus of the class described, a steam chamber and water reservoir, a steam supply connected with said chamber, a nipple carried in a wall of said chamber and communicating with the interior thereof, said nipple having therein a region of reduced pressure upon the passage through the nipple of steam at high velocity, a water outlet pipe connected to said nipple at said region and inside said chamber and extending down into the water in the reservoir, a steam discharge conduit connected with the outlet end of said nipple, and a valve to control the flow of steam and thereby the water through said conduit according to the extent of opening of said valve.

3. In apparatus of the class described, a steam chamber and water reservoir, a steam supply connected with said chamber, a suction-producing nipple connected through a wall of said chamber and communicating with the interior thereof, a water outlet pipe connected to said nipple and with the water in the lower part of said reservoir, a steam discharge conduit connected with the outlet end of said nipple, and a valve in said conduit to control the flow of steam and thereby the water therethrough according to the extent of opening of said valve, the greater the volume of steam passing through the conduit the greater the suction in the nipple until the water is raised and discharged thereinto and becomes mixed with the steam.

4. In apparatus of the class described, a steam chamber and water reservoir, a steam supply connected with said chamber, a nipple connected through a wall of said chamber and communicating with the interior thereof, said nipple having a suction-producing steam passage therethrough, a water outlet pipe from the reservoir connected to said nipple at substantially the suction point thereof, a steam discharge conduit connected with the outlet end of said nipple whereby when steam is discharged in sufficient volume through said conduit water from the reservoir is sucked into and mixed with the steam in the nipple and the mixture discharged through said conduit, and a valve for controlling the volume of flow of the steam through said conduit,

and a valve for controlling the volume of flow of the steam through said conduit according to the extent of opening of said valve.

5. In apparatus of the class described, a steam chamber and water reservoir, a steam supply connected with said chamber, a nipple having a Venturi-like passage therethrough connected with the said steam chamber, a water connection from the said reservoir to the said nipple at the throat of said Venturi passage, a steam discharge conduit connected with the outlet end of said nipple whereby the steam issuing through said conduit at sufficient velocity draws water thereinto through said water connection and discharges the mixture as wet steam, and a valve 10 for controlling the flow of steam and thereby the water through said conduit according to the extent of opening of said valve.

6. In apparatus of the class described, a steam chamber and water reservoir, a steam supply connected with said chamber, a nipple within the chamber having a Venturi-like passage therethrough opening into the said steam chamber, a water connection from the said reservoir to the said nipple at the throat of said Venturi passage, a steam discharge conduit connected with the outlet end of said nipple whereby the steam issuing through said conduit at sufficient velocity draws water thereinto through said water connection and discharges the mixture as wet steam, and a valve for controlling the flow of steam and thereby the water through said conduit according to the extent of opening of said valve.

7. In apparatus of the class described, a steam chamber and water reservoir, a steam supply connected with said chamber, a nipple outside the chamber having a Venturi-like passage therethrough opening into the said steam chamber, a water connection from the said reservoir to the said nipple at the throat of said Venturi passage, a steam discharge conduit connected with the outlet end of said nipple whereby the steam issuing through said conduit at sufficient velocity draws water thereinto through said water connection and discharges the mixture as wet steam, and a valve for controlling the flow of steam and thereby the water through said conduit according to the extent of opening of said valve.

8. In apparatus of the class described, a steam chamber and water reservoir, a steam supply connected with said chamber, a nipple connected with said chamber and having a central bore with angular steam passages thereinto pointing in the direction of flow of steam therethrough, a water pipe connection into the said central bore and communicating therewith adjacent the openings of said angular passages into the central bore, said water pipe connecting into the water in the said reservoir, and a steam discharge conduit connected with the outlet end of said nipple,

a manually controlled valve in said conduit, the steam flowing through the said passages and out through the said bore and through the outlet conduit in sufficient volume when the said valve is opened widely to cause a stream of water from said pipe to be injected into and mixed with steam in the bore and the outlet conduit, the steam issuing in a dry condition when the valve is opened to a less extent.

9. In apparatus of the class described, a steam chamber and water reservoir, an auxiliary water receptacle connected with said reservoir, a steam supply connected with said chamber, a nipple having a Venturi-like passage therethrough having its inner end connected with said steam chamber, a water pipe connected at one end with said nipple at the throat thereof and extending at its other end into said auxiliary receptacle below the water level therein, a steam discharge 20 conduit connected with the outer end of said nipple, and a valve controlling the passage of steam through said conduit, the flow of steam through said nipple at high velocity upon widely opening the valve causing water to be drawn from the 25 water pipe and to mix with the steam issuing from the conduit.

10. In apparatus of the class described, a steam chamber and water of condensation reservoir, a steam supply connected with said chamber, a 30 suction nipple carried in a wall of said chamber and communicating with the interior thereof, a water pipe connection from said nipple to the lower part of the water reservoir, a valve casing connected with the outer end of said nipple, a 35 manually operated valve in said casing and causing the flow of dry steam or mixed steam and water therethrough according to the extent of opening of the valve, and a discharge conduit connected with said valve casing.
